UNITED STATES PATENT OFFICE.

JACOB SCHINNELLER, OF PITTSBURG, PENNSYLVANIA.

FURNACE FOR BURNING HYDROCARBON OILS.

SPECIFICATION forming part of Letters Patent No. 434,092, dated August 12, 1890.

Application filed April 19, 1889. Serial No. 307,665. (No model.)

To all whom it may concern:

Be it known that I, JACOB SCHINNELLER, a resident of Pittsburg, in the county of Allegheny and State of Pennsylvania, have invented a new and useful Improvement in 5 Furnaces for Burning Hydrocarbon Oils; and I do hereby declare the following to be a full, clear, and exact description thereof.

My invention relates to furnaces for burning liquid hydrocarbons for metallurgical and other purposes, its object being to provide a suitable furnace in which the oil-vapor and air can be so intermingled and heated before combustion that a perfect combustion of the 15 hydrocarbons is obtained in the furnace.

My invention relates to the apparatus described in an application for Letters Patent for process of burning hydrocarbons filed by me December 19, 1888, Serial No. 294,072, the 20 process described and claimed in said application consisting, generally stated, in dropping the oil upon a mass of heated balls or lumps of refractory material and drawing air through said refractory material, so intermingling the oil-vapor and air and passing the 25 same from and burning it at the lower or delivery end of said mass.

My present invention consists, generally stated, in a furnace for metallurgical or other 30 purposes having a heating-chamber, an entrance flue or flues at the end thereof, a chamber containing a mass of balls or blocks of refractory material above the flues and having air-entrances therein, and an oil-entrance 35 at or above the chamber, whereby as the oil is sprayed or dropped from the oil-entrance it will percolate between the balls or blocks contained in the chamber and be intermingled with the air therein and be brought into 40 proper condition for combustion at the lower end of the chamber, the intermingled air and oil-vapor being burned in the entrance-flues to the heating-chamber.

It also consists in certain other improvements relating to the heating of the air, the regulation of the flow of the oil and air to the chamber, and the changing of the position of the balls or blocks of refractory material, as 45 will be more fully described.

To enable others skilled in the art to make and use my invention, I will describe the

same more fully, referring to the accompanying drawings, in which—

Figures 1 and 2 are longitudinal sections illustrating my invention as applied where 55 the air is heated or where simply cold air is employed for the purpose, and Fig. 3 is a cross-section on the line *xx*, Fig. 1.

Like letters of reference indicate like parts in each.

My invention, as shown, is applied to a metallurgical furnace—such as for puddling and melting iron—having the hearth or furnace-chamber *a*, the stack or escape-flue *b*, which leads to such a height or through such 65 a length of flue (when a single chimney is employed for a number of furnaces) that a continuous draft can be maintained through the furnace, and in that way the oil-vapor and air can be drawn into the entrance end 70 of the furnace, so as to be burned at the entrance end of and within the furnace-chamber.

At the entrance end of the furnace-chamber are a series of combustion-flues *c*, the entrance-flue being preferably divided into a series of flues, as shown, by brick or tile extending longitudinally of the furnace, for the reason that a support is thus obtained for the blocks or balls of refractory material in the 80 vaporizing-chamber *e* of the furnace, and that the flame is the better confined and controlled within this series of flues. At the entrance end of said flue *c* there is the inlet *c'*, which communicates with either an air-blast pipe or 85 with the atmosphere, a blast or simple draft being employed, as may be desired, said air-inlet *c'* being controlled by a valve *c²*, and, if desired, the air-inlet being divided into several sections corresponding to the series of 90 flues *c*, so as to regulate the combustion within the different flues of the series.

If desired, in order to provide at all times sufficient air to form complete combustion, as well as to prevent the high heat generated 95 therein from melting out the flues *c*, the wall *a²*, supporting brick or tile dividing the flues, may be made comparatively thin and exposed on its lower surface, and inlet-passages *c³* extend up through this wall into the flues *c*, the 100 ingoing air thus aiding in cooling the wall *a²*. The supply of air through these passages *c³*

can be controlled by the door c^4 , communicating with the space under the wall a^2 .

Extending above the combustion-flues c is the casing d , either formed of metal and suitably lined with fire-brick or built entirely of fire-brick, as may be desired, and so forming the chamber e , which in the desired construction is open at the upper or entrance end and lower or delivery end thereof, and is filled, as shown, with a mass composed of balls, blocks, or lumps of fire-brick or other refractory material. I prefer to employ refractory balls g for the purpose, for the reason that they provide for the change in the position of the refractory material within the chamber without great labor, as by opening the lower part of the chamber e —such as by withdrawing the block d , closing the port d^2 at the base of the said chamber e —the balls can be rolled out of the chamber and upon the platform f , and can be subsequently raised and introduced through the open upper end of the chamber e , a port f' being formed above the upper end of the chamber to provide for the introduction of such balls where heated air is employed in connection with the furnace, and said port being closed by a block or plate f^2 . For this purpose the walls of the chamber e are preferably made downwardly flaring, as shown, so that there is no opportunity for the balls or blocks g to bridge within the same, and such portion of the balls as it may be desired to remove from the chamber can easily be rolled therefrom onto the platform. By this means I am enabled to withdraw the balls from the lower part of the chamber close to the combustion-flues c , when they are highly heated by the heat from said flues, and then introduce the highly-heated balls into the upper part of the chamber, so that when the oil drops upon the same it will be the more quickly vaporized and intermingled with the air, while at the same time as the heavier portions of the oil which are not vaporized will adhere to the balls or blocks, such balls or blocks are brought to the lower part of the chamber, where they are subjected to the high heat generated in the combustion-flues, and any such tar or heavy hydrocarbon adhering thereto may be burned from the same.

Arranged at or above the upper end of the chamber f is the oil-supply pipe h , controlled by a suitable valve h' . This pipe has suitable perforations or openings therein, which permit of the dropping or spraying of the oil directly upon the fire-clay balls, so that oil dropping upon the upper end of said body of refractory material will pass between the balls composing the same and descend through the chamber e , the oil coating to some extent the different balls, and also being vaporized by the heat thereof, while the draft through the furnace will draw air through said body of refractory material and intermingle it with the oil-vapor, so that the intermingled oil-vapor and air will finally pass from such chamber e into the combustion-flues c and

be burned therein, a further portion of air being added to it, if desired, through the air flue or entrance c' . In order, however, to provide for the regulation of the supply of air to and the proper intermingling thereof with the oil-vapor, I have formed along the sides of the chamber e a series of flues m , which extend through the brick-work of the chamber-walls and communicate with valves k , said valves being mounted in suitable seats in the casing d , which is provided with suitable bearings for the same. The said valves k are preferably horizontal valves, having at each end seats or journals and at certain points therein enlarged cylindrical portions k^2 to hold them in line and prevent the warping thereof under the high heat and between said bearings and said enlarged portions, the valves being formed flat, as shown at l —that is, of such shape that when turned in one position they close the openings or inlets entirely, and when turned at right angles thereto leave the inlet practically open. The valves may be adjusted to any position between these two, according to the amount of air to be fed to the oil-vapors in the chamber e . The said valves have angular ends k' , by which they may be turned and adjusted, as desired, and when heated air is employed—such as in the apparatus shown in Fig. 1—the angular ends k' of the valves extend out through the furnace-walls, so that they can be properly adjusted. As the oil-supply pipe h , especially the part thereof having the perforations therein, is liable to become gummed with the thicker or heavier portions of the oil, and there is therefore a liability of the perforations becoming clogged, I arrange within this portion of the pipe containing such perforations the spiral cleaner or scraper n , which corresponds in diameter to the internal diameter of the pipe and has a handle n' extending through a stuffing-box at the end of the pipe, thus providing for the turning of the scraper n within the pipe and the freeing or loosening of any gummy matter therein. In order to further provide for the removal of such matters, I also connect with such pipe h a steam-pipe p , which will furnish steam to said pipe and assist in the vaporization of said gummy material and the driving of the same out of the pipe, so that I am enabled to maintain the pipe in proper condition for working, and to give a free escape from said pipe h when it is cleaned the end h^2 thereof is formed open and provided with a valve h^3 , which may be opened during the cleaning operation.

In order to heat the air intermingled with the oil-vapor, I provide suitable air-heating apparatus in the stack or escape flue b , Fig. 1 showing an apparatus suitable for the purpose, such apparatus consisting of the pipes r , passing through the enlarged portion b' above the stack or escape flue. The air-heating pipes may be arranged in said flue in any manner desired. The oil-vaporizing chamber

e is under such circumstances inclosed in such way in a brick or other casing t that all the air flowing thereto passes through the air-heating pipes r, there being a suitable 5 passage s from said pipes to the vaporizing-chamber, and, if desired, all the air may enter through the upper end of said vaporizing-chamber, though I prefer to employ the valves k to regulate the flow of air, as above described, and in such case the valves are also 10 inclosed within the casing t, as shown, and in order to supply the air to the front series of valves said casing has an extension u' over the front portion of the chamber e, forming a 15 flue or space u therein, through which the air may flow to said valves.

When my improved furnace is in use, it may be employed, as above stated, for metallurgical, boiler, or other heating purposes, and 20 the oil or other like hydrocarbons are forced under pressure either from an accumulator or by gravity from a tank and dropped or sprayed from the perforations of the pipe h upon the fire-clay balls g in the chamber e, 25 and said oil continues to percolate downwardly through the openings or interstices between the balls or blocks until it reaches the combustion flue or flues c. In the meantime, the furnace being properly heated, in the 30 form of apparatus shown in Fig. 1, the air in passing through the pipes or flues r is brought to a comparatively high heat, and it then flows through the passages s or u within the casing t into the upper end of the vaporizing- 35 chamber e and through the side ports therein, so intermingling with the oil and assisting in the vaporizing thereof, and the oil-vapor and air flow downwardly into the combustion-flues c, a proper mixture for forming combustion 40 being thus obtained. Upon the entrance of the same into the flues c the oil-vapor is thus burned, combustion being supported by the air intermingled therewith and, if desired, by the air entering through the air-entrance c' at the end of the flues c. A high heat is 45 thus generated, which, on account of the expansion of the gases and the draft through the chimney, is drawn into the heating-chamber a of the furnace to act upon either the metal 50 therein or the surface of the boiler or for other heating purposes, as may be desired, the flame and heated gases being ejected from the flue c into the furnace-chamber. The heated products then pass through the stack 55 or escape flue b, and by passing around the air-heating flues r act to heat the ingoing air, and so provide heated air to vaporize the oil, which drops upon and is supported by the fire-clay balls, and to intermingle therewith 60 for the continuation of the operation.

In order to regulate the supply of air to the chamber e, the flues k may be turned to any desired position, and the supply of air through the air-entrance c' may be regulated in the 65 same manner. When the balls at the base of the chamber become highly heated by opening the port d', they can be withdrawn therefrom,

passing onto the platform f and be introduced through the port f' into the upper end of the chamber e, so bringing the highly-heated 70 blocks or balls to the upper end of such chamber to assist in vaporizing the oil and permitting those upon which the oil had been dropped in the higher part of the chamber to descend therein into the hotter part thereof, and finally 75 to the base of the chamber, where they are exposed to the direct action of the flame and heat in the combustion-flue c, and any tarry or other like matter adhering thereto may be burned therefrom. By the changing of the 80 balls in the manner above described, I am enabled to vaporize the oil more perfectly by the heated balls in the upper part of the chamber and to utilize all of the oil for heating purposes, either by the vaporization thereof 85 or by the burning of the same from the balls when exposed to the heat generated in the combustion-flues. In case the oil-supply pipe h becomes clogged, it can be quickly cleaned by rotating the valve n therein, and, if desired, 90 by passing steam through the same and blowing it out, as above described.

The furnace shown in Fig. 2 is used in practically the same manner, except that there is no heating of the air, the air being drawn 95 through the upper end of the chamber e and through the valve-controlled passages m, and the heat of the mass of balls being maintained by the changing of the same within the chamber e.

By my invention I am enabled to provide for the proper vaporization of the oil as it comes directly from the tank or accumulator, the intermingling of the air in proper quantities to support combustion therewith, the 105 regulation of the combustion of said intermingled oil-vapor and air, and the heat of the air, if desired, and this without the employment of steam for vaporization purposes, and by means of the simple apparatus, which can 110 be operated by unskilled labor, occupies practically no additional room, and can be constructed at a low cost.

What I claim as my invention, and desire to secure by Letters Patent, is—

1. A furnace having a heating-chamber and entrance flue or flues at one end thereof and a chamber containing a mass of balls or blocks of refractory material above the flue or flues and having an oil-entrance at the upper end above such balls and an air entrance or entrances so as to intermingle the oil and air within said chamber, substantially as and for the purposes set forth.

2. A furnace having a heating-chamber, entrance flue or flues at one end thereof, a chamber containing a mass of balls or blocks of refractory material above the flues and having an oil-entrance at the upper end thereof above such balls, and a series of air-entrances in the side walls of such chamber, substantially as and for the purposes set forth.

3. A furnace having a heating-chamber, entrance flue or flues at one end thereof, a

chamber containing a mass of balls or blocks of refractory material above the flues, and having an oil-entrance at the upper end thereof above such balls, a series of air-entrances in the side walls of such chamber, and valves for controlling said air-entrances, substantially as and for the purposes set forth.

5. A furnace having a heating-chamber, entrance flue or flues at one end thereof, an oil-vaporizing chamber containing a mass of balls or blocks of refractory material above the flue and having oil and air entrances therein, and an air entrance or entrances to the combustion-flues below such vaporizing-chamber, substantially as and for the purposes set forth.

10. A furnace having a heating-chamber, entrance flue or flues at one end thereof, an oil-vaporizing chamber containing balls or blocks of refractory material above said flue and having oil and air entrances therein, one or more horizontal air-passages communicating with the entrance end of the flue, and one or more air-passages extending up through the 25 bottom wall of said flue, substantially as and for the purposes set forth.

6. The furnace having the heating-chamber *a*, combustion-flue *c*, oil-vaporizing chamber *e*, having the ports *m* in the side thereof, and the inclosing-casing *t*, communicating with 30 air-heating pipes, and having the extension *u'*, inclosing the front end of the chamber *e*, so as to feed heated air to the ports thereof, substantially as and for the purposes set forth.

7. The furnace having the heating-chamber 35 *a*, combustion-flues *c*, and the oil-vaporizing chamber *e*, inclosed within a casing communicating with air-heating pipes, said chamber *e* having the port *d'* at the base thereof for the removal of the refractory balls therein and 40 said enclosing casing *t* having the port *f'*, for the entrance of said balls to said chamber, substantially as and for the purposes set forth.

In testimony whereof I, the said JACOB SCHINNELLER, have hereunto set my hand.

JACOB SCHINNELLER.
